BUILDING BRICK

Byron E. Scott, St. Paul, Minn.

Application February 16, 1955, Serial No. 34,542

Term of patent 14 years

(Cl. D18—2)

Fig. 1

I claim:

The ornamental design for a building brick, as shown.
